UNITED STATES PATENT OFFICE.

OLIVER S. JENNINGS AND FRED G. VON HOORN, OF MANSFIELD, OHIO, ASSIGNEES TO WESTINGHOUSE ELECTRIC AND MANUFACTURING COMPANY, A CORPORATION OF PENNSYLVANIA.

INCLOSED-SWITCH MECHANISM.

Application filed June 25, 1927. Serial No. 201,313.

Our invention relates to inclosed switch mechanism and particularly to inclosed switches for controlling lighting circuits and small motors.

5 An object of our invention is to provide an inclosed switch wherein the switch and fuse are mounted upon a sheet-metal carrier to constitute a removable unit that is detachably mounted in a sheet-metal housing 10 or box.

Another object of our invention is to provide an inclosed switch having the above-noted characteristics that may be connected to the conductors before the switch mechanism is placed within the housing, and 15 wherein a minimum number of parts are required.

A further object of our invention is to provide an inclosed switch that is simple in 20 construction and inexpensive to manufacture.

These and other objects that will be made apparent throughout the further description of our invention are attained by means of 25 the switch apparatus hereinafter described and illustrated in the accompanying drawings, wherein

Figure 1 is a plan view of an inclosed switch apparatus embodying features of our 30 invention, the cover being partially cut away for the purpose of clearness.

Fig. 2 is a side elevation of the switch box disclosed in Fig. 1.

Fig. 3 is a top plan view of a switch base 35 carrier constituting a part of our invention; and

Figs. 4 and 5 are end elevational views, respectively, of the carrier shown in Fig. 3.

Referring to the drawings, the apparatus 40 includes a sheet-metal housing having a bottom wall 6, side walls 7 and 8, and end walls 9 and 11. A sheet-metal cover 12 is hinged to lugs 13 on the housing by means of hinge rivets 14.

45 The switch unit includes a sheet-metal carrier 15 consisting of a bottom section 16 and flanges 17 and 18 that fit snugly within the housing between the side walls 7 and 8. The carrier is adapted to be secured within the 50 housing and is, therefore, provided with a pair of keyhole slots 19 disposed on offset portions 21 in the bottom section 16. The offset portions 21 engage inward projections 22 in the bottom wall 6 of the housing. The

projections are provided with threaded 55 openings in which attaching screws 23 are threaded. The threaded ends of the screws lie within the recess 24 formed by the projections 22 and, therefore, do not project beyond the outer face of the bottom wall of the 60 housing.

The carrier is secured within the housing by first being inserted so that the enlarged portions of the keyhole slots 19 fit over the heads of the screws 23 which have first been 65 backed away from the inner face of the projections 22. The carrier is then moved downward or longitudinally of the housing so that the heads of the screws extend over the narrow portions of the keyhole slots. 70 The screws are then tightened. Lugs 25 are struck up from the edges of the slots and serve to prevent longitudinal displacement of the carrier with respect to the housing in case the screws become slightly loosened. 75

As indicated in Figs. 1 and 2, the switch apparatus includes an insulating base 26 upon which a hinge contact jaw 27 and a switch contact jaw 28 are mounted. A switch blade 29 is pivotally mounted in the 80 hinge jaw 27 and is movable into and out of engagement with the contact jaw 28 by means of an operating handle or bail 31 that is journalled in bearing openings 32 in the flanges 17 and 18 of the carrier. The 85 bail 31 is connected to the switch blade by means of an insulating clip 33 that is secured to the switch blade by means of rivets 34, the bail fitting in a slot 35, as indicated in Fig. 2.

90 A fuse receptacle 36 for receiving a standard screw-plug fuse (not shown) is mounted on the insulating base 26 in such position that the offset portion 37 of the bail lies above the receptacle, when the switch is in 95 the closed position and prevents removal of the fuse without first opening the switch.

The fuse receptacle and switch are provided with terminals 38 and 39, respectively, to which the line conductors are attached in 100 such manner that the fuse and switch are connected in series.

105 Referring particularly to Fig. 2, the side walls 7 and 8 of the housing are provided with slots 41 of L-shape, the short legs 42 of the slots extending in a direction parallel to the bottom wall of the housing. The slots are provided to permit the bail 31 to move

into them when the carrier 15 is being assembled with respect to the housing. The journal portions 43 and 44 of the bail slide into the portion 42 of the slot 41 when the 5 carrier is moved downward longitudinally with respect to the housing to bring the slots 19 into the locking position with respect to the screws 23. It will be seen that the bail serves to prevent outward detach- 10 ing movement of the carrier and assist the screws 23 in retaining the carrier in assembled position. The bail will serve to retain the carrier in operative position even though the screws 23 should become loosened.

15 The limit stop 45 for limiting the closing movement of the operating handle 31 is struck from the side wall 8, and the hole 46 resulting from the striking of the stop 45 from the side wall, is closed by the flange 18 20 of the carrier. The end of the flange 18 is provided with a limit stop 47 that constitutes an integral part of the flange 18. This stop is engaged by the operating bail or handle 31 when the switch has been moved to its 25 extreme open position.

The flange 18 is also provided with an integral latch tongue 48 that projects through an opening 49 in the cover 12 when the latter is in the closed position indicated in Fig. 30 2. The latch is provided with an integral up-struck lug 51 that snaps over the edge of the opening 49 when the cover is in closed position and serves to releasably retain it in closed position. A hole 52 is provided in the 35 latch 48 through which the hasp of a lock may be inserted for locking the cover in closed position.

From the foregoing, it is apparent that the switch construction is relatively simple 40 and inexpensive, and that the assembly of the switch is facilitated by the unit construction of the carrier and insulating switch base.

Various modifications may be made in the device embodying our invention without departing from the spirit and scope thereof 45 and we desire, therefore, that only such limitations shall be placed thereon as are imposed by the prior art or set forth in the appended claims.

50 We claim as our invention:

1. Inclosed current-controlling mechanism comprising a housing, a carrier for a current-controlling device having side flanges fitting between the walls of the housing, and means on the bottom and side walls of the housing for engaging means on the carrier and flanges when relatively moved longitudinally for preventing withdrawal of the carrier from the housing.

60 2. An inclosed current-controlling mechanism comprising a sheet-material housing having an inward projection in its bottom wall, a threaded attaching screw threaded in the projection and a sheet material carrier for a current controlling device adapted to

rest upon the bottom of the housing and having a portion offset therefrom to seat upon the projection, the said offset portion being provided with a keyhole slot for engaging the said screw and permitting detachment of the carrier from the housing without necessitating removal of the screw from the bottom wall.

65 3. An inclosed current-controlling mechanism comprising a sheet-material housing 75 having an inward projection in its bottom wall, a threaded attaching screw threaded in the projection and a sheet-material carrier for a current-controlling device adapted to rest upon the bottom of the housing and 80 having a portion offset therefrom to seat upon the projection and side flanges for engaging the side walls of the housing, the said offset portion being provided with a keyhole slot for engaging the said screw, the said side walls of the housing being provided with slots of L-shape and the said flanges 85 supporting means for engaging the last said slots for preventing accidental withdrawal 90 of the carrier.

4. An inclosed current-controlling mechanism comprising a sheet-material housing having side walls provided with slots of L-shape, a sheet-material carrier for a current-controlling device having flanges engaging 95 the said side walls of the housing, an operating shaft for the said device carried by the flanges and engaging the said slots for preventing accidental withdrawal of the said 100 carrier from the housing.

5. An inclosed current-controlling mechanism comprising a sheet-material housing having side walls provided with slots of L-shape, a sheet-material carrier for a current-controlling device having flanges engaging 105 the said side walls of the housing, an operating shaft for the said device carried by the flanges and engaging the said slots, the said housing having an adjustable attaching means on the bottom wall thereof and the 110 said carrier having a keyhole slot for engaging the said means, the said adjustable means and operating shaft serving to prevent accidental withdrawal of the carrier from the 115 housing.

6. An inclosed current-controlling mechanism comprising a sheet-material housing having side walls, a sheet-material carrier for a current-controlling device having flanges adjacent the said walls of the housing, an operating means for the said device, a limit stop for the said means struck from a side wall of the housing at a point covered by a flange of the carrier, the said flange serving to cover the opening resulting from 120 striking out the said stop.

7. An inclosed current-controlling mechanism comprising a sheet-material housing having side walls, a sheet-material carrier for a current-controlling device having 130

flanges adjacent the side walls of housing, a hinged cover for the housing having an opening, and a yielding extension integral with the said carrier for projecting through the said opening and serving to releasably retain the cover in closed position.

8. Inclosed switch mechanism comprising a housing, an insulating base, a carrier therefor to which the base is attached for assembly as a unit within the housing, the said

housing having adjustable attaching means and the said carrier having a keyhole slot for cooperating with the said means, whereby the carrier is detachably secured within the housing.

In testimony whereof, we have herento subscribed our names this 18 day of June, 1927.

OLIVER S. JENNINGS.
FRED G. VON HOORN.
